AMALGAMATOR

John D. Niles, Elk City, Idaho

Application July 3, 1937, Serial No. 151,917

4 Claims. (Cl. 209—42)

The present invention relates to amalgamators for separating precious metals from ore and comprises essentially a vessel holding a body of mercury and means for passing mixed pulverized ore and water through and in close contact with the body of mercury in the vessel.

An object of the present invention is to provide an amalgamator of this character embodying a horizontal plate mounted for rotation with the vessel and upon which the pulp from the vessel is discharged, said plate being silver-coated and having skimmers associated therewith for smoothing the pulp over the surface of the plate as the same is rotated to cause any of the precious metal laden mercury which might be discharged with the pulp to adhere to the plate for reclaiming the same.

A further object is to provide an apparatus of this character of simple and practical construction, relatively inexpensive to manufacture and maintained in operation, efficient and reliable in performance and otherwise well adapted for the purposes for which the same is intended.

Other objects and advantages reside in the details of construction and operation as more fully hereinafter described and claimed, reference being had to the accompanying drawings forming part hereof, wherein like numerals refer to like parts throughout and in which:—

30 Figure 1 is a vertical sectional view through the apparatus.

Figure 2 is a top plan view with the upper portion of the feed pipe shown in section.

Figure 3 is a horizontal sectional view taken substantially on a line 3—3 of Figure 1.

Figure 4 is a bottom plan view.

Figure 5 is a fragmentary sectional view taken substantially on a line 5—5 of Figure 2 and showing one of the rifles.

40 Figure 6 is a plan view of the bottom of the bowl or vessel.

Referring now to the drawings in detail, wherefore for the purpose of illustration I have disclosed a preferred embodiment of the invention, the numeral 5 designates a frame which includes bottom frame members 6 of substantially square shape, said bottom frame having an inner annular frame 7 connected to the bottom 6 by braces or arms 8. The frame also includes upper standing frame members 9 connected by top frame members 10.

The annular bottom frame member 7 is formed with an inwardly extending flange 11, the upper surface of which is grooved for receiving a set 50 of ball bearings 12 upon which an annular car-

riage 13 is mounted for rotation. The upper surface of the carriage is provided with a ring gear 14 operatively engaged by a pinion 15 driven by a shaft 16 extending from the frame and operated by a suitable source of power.

Braces 17 extending upwardly from the carrier 13 and have their upper ends extended inwardly for fixedly attaching to a mercury bowl or vessel 18, said vessel being suspended from the bracket within an opening 19 formed in the center of the carrier as will be apparent from an inspection of Figure 1 of the drawings.

A removable bottom 20 is threaded in the lower walls of the vessel, said walls tapering upwardly and terminating in an internally threaded neck 15 21. A tubular discharge pipe 22 has its lower end extended within the neck 21 of the vessel, said pipe being externally threaded as at 23 intermediate its ends for threaded engagement with the neck. The tubular member is secured in 20 threadedly adjusted position by set screws 24.

Adjacent the upper end of the tubular pipe 22 is fixedly secured a horizontal annular plate 25 having a down-turned outer edge 26 formed into a trough 27 extending entirely around the edge of 25 the plate. The outer edge of the trough terminates on a plane below the surface of the plate to permit pulp to spill from the trough into an annual launder 28.

A plurality of rifles 30, formed of copper strips 30 are secured within the bottom of the launder 28, said launder also being provided with a discharge chute 31 at one side thereof.

A plurality of socket members 32 are formed on the upper surface of the bottom 20 of the vessel within which legs 33 are inserted formed on the bottom of a feed pipe 34 extending vertically in spaced relation from the walls of the pipe 22 into the vessel 18, said legs serving to support the bottom of the pipe above the bottom of the 40 vessel. The upper portion of the pipe is supported in vertical position within a ring member 35 connected to the upper frame members 10, said ring member also forming a raceway for a set of ball bearings 36 to facilitate rotation of the 45 feed pipe. To the upper end of the feed pipe is telescopically fitted a funnel or hopper 37 secured in position by set screws 38.

The frame members 10 extend radially from the ring member 35 and are provided with hinge 50 members 39 from which arms 40 are suspended, the lower ends of said arms having skimmers 41 attached thereto by a pin and slot connection 42 to permit vertical adjustment of said skimmers. The lower edge of the skimmers are positioned 55

in cooperating relation with the upper surface of the plate 25 for a purpose as will presently be explained. The outer ends of the skimmers overlie the trough 27 and are provided with depending spaced apart agitator pins 43 which enter the trough to agitate the pulp therein.

In the operation of the device the vessel or bowl 18 is supplied with a quantity of quick silver or mercury and the ore is fed into the funnel or hopper 37 and mixed with the mercury where 10 the precious metal is extracted. By reason of the rotation of the carrier 13 and vessel 18 the pulp is forced upwardly between the pipe 22 and pipe 34 where it is discharged over the upper edge 15 of the last-named pipe onto the silver-plated copper plate 25. The skimmers 41 cause the discharged pulp to come into close contact with the surface of the plate to cause the adherence thereto of any particles of precious laden mercury 20 which might be discharged with the pulp. The pulp is then discharged into the trough or launder 28 and discharged from the machine through the chute 31. The ore which amalgamates with the mercury may be removed by removing the 25 bottom 20 of the vessel and the supply of mercury replenished.

It is believed the details of construction and operation of the apparatus will be readily understood from the foregoing without further detail 30 explanation.

Having just described the invention what I claim is:—

1. In an amalgamator, a rotatable carrier, a vessel adapted to contain mercury and having a discharge upstanding neck, a removable bottom 35 for the vessel, means supporting the vessel in a suspended position from the carrier, a feed pipe leading to the vessel legs on the lower end of the pipe supporting the same on said bottom 40 and maintaining the lower end of the pipe in concentrically spaced relation in said neck, and a horizontal rotatable plate arranged for receiving pulp discharged from the vessel.

2. In an amalgamator, a rotatable carrier, a vessel adapted to contain mercury and having a discharge upstanding neck, an upstanding discharge pipe adjustably mounted on the neck, a removable bottom for the vessel, means supporting the vessel in a suspended position from 45

the carrier, a feed pipe having its lower end positioned in the vessel and extending upwardly in spaced relation from the wall of the discharge pipe, legs on the lower end of the pipe supporting the same on said bottom and maintaining the lower end of the pipe in concentrically spaced relation in said neck, and a horizontal rotatable plate secured to said discharge pipe below its upper edge and arranged for receiving pulp discharged from the vessel. 5

3. In an amalgamator, a rotatable carrier, a vessel adapted to contain mercury and having a discharge upstanding neck, an upstanding discharge pipe adjustably mounted on the neck, a removable bottom for the vessel, means supporting the vessel in a suspended position from the carrier, a feed pipe having its lower end positioned in the vessel and extending upwardly in spaced relation from the wall of the discharge pipe, legs on the lower end of the pipe supporting the same on said bottom and maintaining the lower end of the pipe in concentrically spaced relation in said neck, and a horizontal rotatable plate secured to said discharge pipe below its upper edge and arranged for receiving pulp discharged from the vessel, 10 a trough at the outer edge of the plate having a relatively low outer wall, and a launder positioned outwardly of the trough for receiving the pulp therefrom. 15

4. In an amalgamator, a rotatable carrier, a vessel adapted to contain mercury and having a discharge upstanding neck, an upstanding discharge pipe adjustably mounted on the neck, a removable bottom for the vessel, means supporting the vessel in a suspended position from the carrier, a feed pipe having its lower end positioned in the vessel and extending upwardly in spaced relation from the wall of the discharge pipe and a horizontal rotatable plate secured to said discharge pipe below its upper edge and arranged for receiving pulp discharged from the vessel, a trough carried by the plate and extending around its outer edge said trough having a relatively low outer wall, a stationary skimmer adjustably mounted in vertically spaced relation with respect to the plate and agitators carried by the skimmer and positioned in the trough. 35 40 45

JOHN D. NILES.
